UNITED STATES PATENT OFFICE.

SOLOMON KAMELGAR, OF PATERSON, NEW JERSEY.

STOP MOTION FOR LOOMS.

Application filed July 9, 1921. Serial No. 483,434.

To all whom it may concern:

Be it known that I, SOLOMON KAMELGAR, a citizen of the Republic of Poland, residing at Paterson, in the county of Passaic, and State of New Jersey, have invented certain new and useful Improvements in Stop Motions for Looms, of which the following is a specification.

This invention relates to stop motion mechanisms for looms designed to prevent smashes from occurring, due to the presence of a shuttle already in a box when the picking means operates to move another shuttle into the same; for example, see my patent No. 1,358,214. Such mechanisms are usually constructed with a dagger to actuate stopping mechanism and whose position for that purpose is determined by feeling devices, as protector rods, one for the box or boxes at each end of the batten; and heretofore this dagger was adapted to actuate the stopping mechanism on the forward stroke of the batten. In the case of a box loom there is a condition which may arise in which the mechanism would fail to prevent a smash; this condition arises out of the fact that the changing of the boxes in a box loom takes place when the batten is forward and will arise thus, for example: whenever the weaver, after a stopping of the loom, places a shuttle in a box which at the time of starting is not aligned with the batten but becomes aligned therewith when, the batten being forward, the changing of the boxes takes place. The improved mechanism is characterized by the employment of a dagger which actuates the stopping mechanism on the backstroke of the batten—that is, at a point so far delayed in the cycle of the batten's movement from the time of one pick to that of the next that it will take care of a smash-producing disposition of the shuttles under any condition, including that explained above.

45 In the drawings,

Fig. 1 is a plan showing the batten structure, the breast-beam-including part of the loom frame and my mechanism, the batten structure being more or less back;

50 Fig. 2 is a vertical sectional view of what is shown in Fig. 1 and showing also the crank-shaft and pitman, the batten structure being approximately fully forward and the dagger *l* being in the normal or depressed position so that as the batten reciprocates its hook *l'* will play under the lever *2*;

Fig. 3 is a vertical sectional view of what is shown in Fig. 1 on a larger scale, the batten structure just starting to recede and the dagger *l* being raised by the falling of the block *m* so that its hook *l'* is now in position to catch and pull on lever *2* and so act therethrough and through crank *4* to turn the rock-shaft *f* for stopping the loom and shifting cam-hump *h* to downwardly projecting position;

Fig. 4 is a front elevation of certain parts at the moment when the downwardly projecting cam-hump *h* acts to depress the dagger *l* (as the batten structure continues receding) clear of lever *2* and reset it and block *m*; and

Fig. 5 is a plan of the parts shown in Fig. 4 in the positions they occupy in that figure. The loom frame *a*; breast-beam *b*; batten *c*; single shuttle-box *d*; vertical series of shuttle-boxes *e* moved up and down in the usual way by any known means; the binder *e'* for each of the shuttle boxes; the knock-off shaft *f* journaled under the breast-beam and the handle *f'* thereon; the plate *i* formed with a vertical dovetailed groove *j* and having a depending arm *k*; the block *m* slideable in said groove and normally held down by gravity and a spring *n* and having a depending stem *m'* and a cross-cut or horizontal groove *o*; and the aligned detecting or protector rods *p* journaled in brackets *q* on the batten and each having at its inner end a crank *r* engaged in groove *o* of the block and held therein by a spring *t* coiled about the rod and secured at its respective ends to a collar *u* on the rod and to the bracket *q*, the outer end of the protector rod adjoining the series of boxes having an arm *v* which bears against the shuttle-binders *e'* of those boxes and the outer end of the other protector rod having a crank *w* which bears upon the forwardly projecting arm of a lever *x* bearing against the binder *e'* for the single box *d* are or may all be the same as in my said patent.

The element *g* in the present case is a cam fixed on the knock-off shaft *f* in such relation that when the shaft has been rocked to stop the loom the hump or toe *h* on the cam projects downwardly.

The dagger *l*, pivoted to arm *k* and having stem *m'* pivotally connected to its rear end, has a forward laterally deflected hook *l'* and an upstanding depresser arm *l''* which plays back and forth with the batten in

- vertical plane of and under the cam g . Said hook, when the batten moves back and forth, normally plays under and clear of one end of a lever 2 fulcrumed in a bracket 5 on the breast-beam, the other end of said lever being back of a depending crank 4 on the knock-off shaft f which, when said shaft is in the position for starting the loom, holds said lever in the position shown by 10 dotted lines in Fig. 5, the movement of said lever toward said position being yieldingly limited by a spring 5; said lever is prevented from moving too far in the other direction by the spring 6.
- 15 Figure 2 shows the crank-shaft 7, turning in the direction of the arrow, and the pitman 8 connecting the crank-shaft and batten. The shuttle-box-changing occurs when the batten is approximately fully forward, and 20 the picks or shuttle-flights when the batten is back. Under normal conditions with the loom in motion (handle f' being then in full-line position, Figs. 2 and 3) the block m will be held elevated and so the dagger hook l' will as in Fig. 2 play back and forth under and so miss the lever 2. But if perchance a shifting of the boxes e brings a shuttle in line with the lay while there is also one present in box d , since both rods p 25 (instead of only one, as under the normal condition) have then been moved by the shuttles clear of the block, the latter will fall and raise the dagger to such position (Fig. 3) that its hook l' will catch and pull 30 on lever 2, which by contact with crank 4 will start the knock-off shaft to rock to the stopping position (it being as usual spring-pressed to that position), this occurring when the batten is performing its back-stroke. Incidentally, the cam g having been turned with the knock-off shaft to such a 35 position that its hump h is down (dotted lines, Fig. 3), as the batten proceeds back, and before with the stopping of the loom 40 it comes to a standstill, the depresser arm wipers against said hump, the resulting depressing of the dagger clearing its hook l' from the lever 2 and elevating the block m to position to be re-held by one of the rods 45
- p as soon as the interfering shuttle has been removed.
- 50 Looms are usually constructed so as to stop with the crank of the crank-shaft down (dotted lines, Fig. 2), and if the batten should be moved from the corresponding 55 position it is usual for the weaver to return it thereto on starting up. Assume that, upon a stopping, the weaver by mistake has placed a shuttle in a box of the series e not then alined with the batten but which will 60 become alined with the batten when, upon starting, the boxes change on the batten next reaching the forward position. Then when, 65 on such starting and the batten reaching the forward position and the boxes changing, the batten goes back the mechanism will cause stopping of the loom in the way explained.
- Having thus fully described my invention, what I claim as new and desire to secure by Letters Patent is:—
- 70
- In combination, with the loom frame, and a batten structure movable in the frame backward and forward and having a shuttle box at one end and a shiftable series of shuttle boxes at the other end thereof, a movable system of parts on the frame including a knock-off member, another movable system of parts on the batten arranged in position 75 to clear the first system but normally urged to position to engage and move the same during a backstroke of the batten, and separate detecting members each normally holding the second system in the first-named position, one of said members being actuatable to release the second system by a shuttle present in the first-named box and the other being actuatable to release said second system by a shuttle present in the box of said series which happens to be alined with the 80 batten, and the first system having means on movement thereof to engage during said backstroke the second system and return the latter to position to be held by one of said members.
